UNITED STATES PATENT OFFICE.

THERON W. CHAPMAN, OF LAKEWOOD, COLORADO.

ROCK-DRILL.

SPECIFICATION forming part of Letters Patent No. 542,010, dated July 2, 1895.

Application filed August 27, 1894. Serial No. 521,362. (No model.)

To all whom it may concern:

Be it known that I, THERON W. CHAPMAN, a citizen of the United States of America, residing at Lakewood, in the county of Jefferson and State of Colorado, have invented certain new and useful Improvements in Rock-Drills; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in rock-drills, and consists of the features, arrangements, and combinations hereinafter described and claimed, all of which will be fully understood by reference to the accompanying drawings, in which is illustrated an embodiment thereof.

In the drawings, Figure 1 is a side elevation of the drill, partly in section. Fig. 2 is a top or plan view partly in section. Figs. 3, 25 4, and 5 are sections taken on the lines $x-x$, $y-y$, and $z-z$, respectively, Fig. 1. Fig. 6 is a vertical longitudinal section taken through the keeper located on the threaded reciprocating shaft, the parts being shown on a larger scale. This section may be considered taken 30 on the line $v-v$, Fig. 7. Fig. 7 is a section taken on the line $p-p$, Fig. 6.

Similar reference characters indicating corresponding parts in the views, let the numeral 35 5 designate a casing composed of two parts fastened together in any suitable manner, as by passing bolts through apertured lugs 5^a, formed integral with the casing parts. This casing is adapted to be adjustably secured to 40 any suitable stationary support. For this purpose the casing is provided with an apertured projection 5^c. Within this casing 5 is located a shaft 6, whose central portion is provided with a screw-thread. The extremity 6^a 45 of this shaft forms a chuck or socket for the reception of the drill-bit. Located on the threaded portion of the shaft is the keeper 7, composed of the collar 7^a, slotted to receive the dogs 7^c, which are pivoted on pins 7^d and 50 notched to engage the screw-threads of the shaft. To one end of the collar are attached the leaf-springs 7^b, which engage the dogs and

55 maintain them normally in engagement with the shaft, whereby the keeper is locked thereon. The pivot pins pass through the rear extremities of the dogs or the ends farthest to the left, referring to Figs. 1 and 2. The opposite extremities of the dogs are curved outwardly, as shown at 7^j, to engage beveled stops 8, formed in the casing and adapted to throw 60 the dogs outwardly sufficiently to disengage their teeth from the screw-threads of the shaft, whereby the latter is released from the keeper. The stops 8 are so located that the dogs engage the stops and release the shaft 65 just before the latter reaches its forward limit of movement, or just before the drill-bit engages the rock. Hence the shaft being released from the keeper at the proper moment feeds itself into the rock during every 70 forward stroke of its reciprocation.

The teeth of the dogs 7^c diminish in depth from the parts 7^j rearwardly or toward the pivot-pins 7^d, in order that all the teeth of each dog may disengage or leave the screw-thread of the shaft simultaneously. The collar 7^a of the keeper is provided with projections 7^m, located on diametrically opposite sides thereof and formed integral therewith or attached thereto. Surrounding the shaft 80 6, to the rear of the keeper, is a coil-spring 9. The forward extremity of this spring engages the keeper, while the rear extremity thereof bears against a stop formed on the casing. Located on the shaft forward of the keeper is 85 a collar 10, having inclined ridges, projections, or teeth arranged thereon at regular intervals, whereby they are equidistant from one another.

The shaft is provided with a groove 6^c, which 90 engages a counterpart spline or feather formed on the collar 10, whereby the shaft is permitted to move longitudinally in the collar. The casing is provided with a circumferential groove which locks the collar against 95 longitudinal movement on the casing, but permits it to rotate with the shaft.

In the casing above the keeper is journaled a transverse shaft 12, carrying S-shaped cams 13, one of which is adapted to engage the inclined projections on collar 10, while both of said cams engage the projections 7^m of the keeper as the cam-shaft is rotated. It will be observed that the projections on the collar 10

protrude through an opening in the casing, while the casing is slotted to allow the projections 7^m to protrude therethrough and slide longitudinally therein. To one extremity of 5 the cam-shaft is attached a hand-crank 14, through whose instrumentality the shaft may be rotated.

From the foregoing description the operation of the device will be readily understood. 10 As the cam-shaft is rotated, the S-shaped cams first engage the projections 7^m of the keeper and carry the shaft 6 and the keeper backward compressing the coil-spring. The 15 cams 13 are so shaped that while the shaft is making the backward movement one of the cams engages a projection on the collar 10 and gives the drill-bit a partial rotation. As soon as the keeper is released from engagement with the cams, the shaft 6 is forcibly driven 20 forward by the recoil of the spring 9, and just before the drill reaches the rock the dogs of the keeper engage the beveled stops on the casing and disengage the keeper from the drill-shaft, the momentum of which drives the 25 drill forward into the rock at each successive forward stroke. After each forward stroke of the drill-shaft and as the cams again engage the projections 7^m of the keeper and begin to force the latter backward from the stops 30 8 of the casing, the springs 7^h force the dogs to engagement with the shaft 6, which is again carried backward, given a partial rotation, and released, as already described.

Having thus described my invention, what 35 I claim is—

1. In a rock drill, the combination with the casing, of a longitudinally movable screw-threaded shaft 6 mounted on the casing and carrying a drill bit, a rotatable shaft 12 journaled in the casing and carrying cams, a keeper comprising a collar surrounding the shaft 6, and spring-actuated dogs or grippers pivoted on the collar and threaded to engage the screw threads of the shaft whereby the 40 keeper and shaft are normally locked to—

gether, the collar of the keeper having lateral projections lying in the path of the cam on shaft 12, stops located on the casing and adapted to engage the dogs and unlock the keeper while the shaft is making the forward movement, substantially as described.

2. In a rock drill, the combination with the casing, of the longitudinally movable shaft 6 supported on the casing, a rotatable shaft 12 journaled in the casing and carrying an S-shaped cam, the keeper normally locked on the shaft and carrying a projection lying in the path of the cam, a collar surrounding the shaft and locked from longitudinal movement on the casing, the shaft and collar being connected by a spline on one part engaging a groove in the other part, the collar being provided with exterior projections all lying successively in the path of the cam, the casing being shaped to engage and unlock the keeper during the forward movement of the shaft 6, substantially as described.

3. In a rock drill, the combination with the casing, of a longitudinally movable screw-threaded shaft 6 supported on the casing, the 70 notched spring-actuated grippers engaging said shaft, a rotatable shaft 12 journaled in the casing and carrying a cam, a collar surrounding the shaft 6 and locked from longitudinal movement on the casing, the shaft 6 and the collar being connected by a spline on one part engaging a groove on the other part, the collar being provided with exterior projections all lying successively in the path of the cam, whereby as the shaft 12 is rotated, 75 the partial rotation between strokes is imparted to the drill shaft 6, substantially as described.

In testimony whereof I affix my signature in the presence of two witnesses.

HERON W. CHAPMAN.
